UNITED STATES PATENT OFFICE.

JAMES B. THOMPSON AND SELDON B. HIBBARD, OF PORTLAND, OREGON.

ART OF REFRIGERATION AND APPARATUS THEREFOR.

Application filed February 26, 1924. Serial No. 695,233.

To all whom it may concern:

Be it known that we, JAMES B. THOMPSON and SELDON B. HIBBARD, citizens of the United States of America, and residents of 5 Portland, in the county of Multnomah, in the State of Oregon, have invented certain new and useful Improvements in the Art of Refrigeration and Apparatus Therefor, of which the following is a specification, reference being had to the accompanying drawings.

Our invention comprehends improvements in the art of refrigeration, and has for its principal object the production of a simple, 15 economical, and efficient refrigerating machine for domestic and similar uses.

The efficiency of our machine is in great measure augmented by the novel method employed in connection with it, for example, 20 for the separation of the refrigerant and of the lubricant or oil as commonly used in ice machines. Every ice machine, like any machine which has working parts, requires, of course, provision for its proper lubrication; but in ice machines, from the very nature of them, a peculiar difficulty has been experienced which practically forbids that the refrigerant on which the machine operates shall be altogether separated from contact with the lubricant employed therein, although it also requires that it shall be uncontaminated thereby. The difficulty arises not so much because the presence of the lubricant in the refrigerant interferes with the 30 simple reduction of temperature, which it is the first essential function of the machine to effect; but because afterwards the presence of even a slight trace or residue of the lubricant in the refrigerant has a cumulative tendency to deposit a film of lubricant upon the inner walls of the expansion chamber or coils of the machine through which the said reduction of temperature is made effectually available for use.

45 The progressive result of such deposit is by insulation to impair the efficiency of the refrigerative action of the machine so that it will be, in a brief space of time, either materially or altogether suspended.

That difficulty is practically eliminated by our invention through the provision in the refrigerant circulatory system of our machine of two substantial bodies of liquids of different specific gravities, one of oil, for example, and the other of a refrigerant. Each of said bodies is held constantly in a

state of substantially perfect rest at some point in said system through which the circulatory medium must pass in order to accomplish its cycle of circulation. Now, theoretically, the only medium which is necessarily circulatory in such a system is the refrigerant. It is that which in the course of its circulation effects refrigeration by undergoing alternate compression and expansion in repeated cycles of circulation.

Practically, however, the refrigerant, in the course of each cycle of its circulation, catches up and carries with it some modicum of the oil or other lubricant whose presence 70 the proper lubrication of the mechanism used for compressing the refrigerant demands. Without effectual means for the separation of the lubricant from the refrigerant before the latter reaches the expansion coils of the machine, the objectionable result already specified follows of film-coating the inside of said coils, that is to say, the refrigerating element of the machine.

The difficulty above explained is well recognized in the art, and many different methods have been heretofore attempted for obtaining effective separation of the lubricant out of the refrigerant. Among those methods, separation of those liquids through the 80 utilization of the mere differences in their respective specific gravities has been tried, but with indifferent success. From all attempts of that description, however, the principle of our invention is broadly distinguished by the fact that while we effect separation by utilizing the difference of specific gravities of two liquids, we are enabled to do so to a degree of substantial perfection 85 by bringing the liquids together in bodies 90 which are in a state of static stability. By this means the full effect of the relative buoyancy of the two liquids is obtained as a factor of separation.

In the operation of our machine the body 100 of the refrigerant is being constantly, but so very slowly as not to impair its static stability, drawn off into circulation from the bottom of the body of the refrigerant where it lies confined at rest in sufficiently 105 undisturbed repose to permit it, before it is called into circulation, to become entirely freed of any contamination by the lubricant which collects and rests in a separated body upon it. In the circulatory movement of 110 the refrigerant a continuing separation therefrom of the lubricant is not only ef-

fected by what may be denominated a straining operation of the force of gravitation acting upon their different specific gravities as soon as the two liquids are brought into relationship that is favorable to such operation; but afterwards, also, when the two liquids come to rest in their respective pools, as the bodies of the respective liquids may be designated, there is a further continuing tendency of the heavier liquid, namely the refrigerant, to cleanse itself entirely of the presence of even a trace of the liquid of lower specific gravity, namely the lubricant, by action of the relative buoyancy of the two liquids. That is to say, so long as the two liquid bodies are maintained in a state of rest and in the relationship in which the lighter is superposed above the heavier, opportunity is afforded for separation through the lifting up of the more buoyant liquid out of the heavier liquid and the precipitation of the heavier liquid towards the bottom of the pool. This, too, is the result of the force of gravitation, but it is made available by the bringing of the two liquids substantially to static stability. In order to furnish supply of the medium of circulation which the demands of its circulation make upon it, the heavier liquid (the refrigerant) is separately drawn off, so slowly as to be without disturbance of the operative static stability of the body from the bottom of the lowermost pool.

Also, a sufficiency of the lubricant is drawn off in like manner to meet the demands made upon it for the lubrication of the working parts of the machine. This too is accomplished without disturbance of the static stability of the body of the lubricant.

The draughts upon the body of the refrigerant and that of the lubricant, respectively, are made always of slow and gradual flow. Consequently, there need be no cause, in any instance, for apprehension that there may ensue in the operation of the machine a demand in excess of the supply of either liquid. It may be observed, however, that the presence of a small admixture of the refrigerant with the lubricant is immaterial. In fact the refrigerant is in itself of sufficient lubricating quality to permit the machine to be kept running for short periods at a time without injurious results, even if no other lubricant is present.

The object of that separation of the two liquids which is material is to keep the refrigerant while in circulation through the expansion chambers of the machine substantially clean of oil or other film-forming lubricant.

Other objects of our invention besides those above indicated will be apparent to one skilled in the art from the following specification.

What constitutes our invention will be hereinafter specified in detail and succinctly set forth in the appended claims.

In the accompanying drawings we illustrate our invention in one form of embodiment which is preferred for its simplicity and economy of construction and operation.

Of said drawings—

Figure I is a side elevation of our machine, partly broken away to show part of its interior, and with the usual enclosing case or chest for the expansion coils omitted.

Figure II is an end elevation of the machine taken from the end opposite that on which the expansion coils are located.

Figure III is a top plan view of part of the subject matter of Figure I.

Figure IV is a longitudinal horizontal section of the compression pump-case of our machine showing the piston therein in full.

Figure V is a similar view of part of the subject matter of Figure IV, the section thereof being taken at right angles to the view in the preceding figure.

Figure VI is a section on the line VI—VI of Figure IV.

Referring to the numerals on the drawings, 1 indicates the bed frame or pedestal of our machine which may be of any suitable weight, material, form, and dimensions.

It is provided on one end with a preferably cylindrical pump-case 2, and on the opposite end with a supporting piece 3, upon which is provided a journal box 4. The member 3 cooperates with a corresponding piece 5 on top of the case 2 for the support of a closed receptacle 6 constituting a condensing and separating chamber.

The case 2 is preferably provided with opposite removable heads 8 and 9, secured to it preferably by screw bolts 10, and is also provided with a side cap 11, secured to it as by screw bolts 12.

The cap 11 is provided with a journal bearing that is coaxial with the box 4, in conjunction with which it serves for the support of a rotative shaft 15.

The said shaft is provided on its outer end with a suitable drive pulley 16 which is fixed to it. At its opposite end the shaft 15 carries an eccentric-head 17, which is fixed thereto and which rotates within the case 2 in a plane parallel to that in which the line of its longitudinal axis lies.

The interior of the case 2 is fitted with a double-acting piston 18, which, with snug fitment within the bore of the case, maintainable, for example, by packing rings 19, reciprocates between the opposing faces of the heads 8 and 9.

The eccentric-head 17 works in a snug fitting recess provided for it in a box 20 let into and secured to the piston 18. Surrounding said working parts is a housing 22 provided for it in and preferably incor-

porated with the wall of the case 2. The housing 22 constitutes an enclosure for an oil bath for the said working parts and for the piston enclosed within it.

5 A pipe 25 communicates, by way of two branch pipes 26 and 27 with which it is provided, with the interior of the case 2, the branches being operatively connected, respectively, with the heads 8 and 9, and the 10 pipe 25 with the expansion coils 28 which constitute a simple and therefore preferred expansion chamber for the machine. The pipe 25 is preferably provided with a valve 29 for opening and closing it, and with a 15 suitable pressure gauge 30.

31 indicates a transverse pipe which communicates with the interior of the receptacle, as through a removable dome 32 thereon, and with two branch pipes 33 and 34 leading into the interior of the case 2 through its heads 8 and 9, respectively. The pipe 31 is joined to its two branches 33 and 34, as by a cross fitting 35, upon opposite sides of which, respectively, are provided valves 37 and 38, 20 the former being a purge valve, and the latter one for control of fluid flow through the pipe 31. The case of the valve 37 may 25 constitute a liquid-supply intake port.

Each of the heads 8 and 9 is provided within with a conduit 40 which, when the heads are in place on the case 2 (compare Figs. IV and V) communicates at one end with the interior of said case, and at the other with a cross-conduit 41, with the terminals 42 and 43 of which, respectively, the branch pipes 26-27, and the branch pipes 33-34 are operatively conjoined above elbows 44 therein, as by aid of a union 45, 45', threaded upon the end of the pipe and within the cross-conduit terminals, in each instance.

Fluid flow through the respective cross-conduits in the heads 8 and 9, respectively, is controlled by automatic valves 46 and 47 which open, respectively, in opposite directions, whereby fluid under pressure from the piston 18 within the case 2 is permitted to open the valve 46 but is entrapped by the valve 47. Reciprocating movement in one direction of the piston 18 effects pressure alternately in each of the cross-conduits 41. Reciprocation of the piston in the opposite direction produces a suction which, between intervals of compression is enabled to draw only upon the fluid contents of the pipe 26 or 27 by reason of the fact that the valve 46 opens under pressure, and that the valve 47 closes thereunder but opens under suction.

For the accomplishment of its function, 30 the valve 46 is made to close against an annular seat 50 formed in the wall of the bore of the conduit terminal 43, whose diameter is, for the accommodation of the seat, enlarged, as shown in Figure VI. The stem 51 of the valve 46 works in a sleeve 52 de-

pending from a diaphragm 53 which is secured against a shoulder 54 provided for it in the outer end of the terminal 43, above the valve seat 50, by impingement against the diaphragm of the inner end of the 70 union 45. The diaphragm is provided with a ring of apertures 55 through which fluid may flow to the pipe 33 or 34, as the case may be, the inner end of the bore of the union 45 being outwardly flared, as indicated at 56, so as to take in the outer circumference of the ring of apertures 55. A spring 57, coiled about the stem 51 and seated at opposite ends, respectively, against the diaphragm 53 and the top of the valve 46, 80 serves to keep said valve normally but yieldingly closed against its seat 50.

The valve 47 has a stem 58 working in a sleeve 60 provided in the wall of the conduit 41 and disposed coaxially with the conduit terminal 42. The valve is yieldingly projected outwardly by a spring 61 coiled about the sleeve 60. By said spring it is normally impelled into close contact with a seat 62 provided for it in the opposing end of a 90 sleeve 63. Said sleeve is slipped into the bore of the terminal 42, whose diameter is sufficiently enlarged to form within said terminal an annular shoulder 65, against which the sleeve is confined by impingement 100 against its outer end of its proper union 45.

By virtue of the arrangement just described of the valves 46 and 47 in the respective heads 8 and 9, provision is made so that with every alternate stroke, the piston 18 will suck fluid from the pipe 26 or the pipe 27 into one of the cross-conduits 41 and will therein compress and thence expel each charge of fluid so derived into the pipe 33 or the pipe 34. The valves 46 and 47, respectively, yield to the suction as often as it occurs through reciprocation in one direction of the piston 18, and the valve so actuated instantly closes upon the reverse stroke of the piston. Likewise the valve 46 opens to the force of compression generated by a forward stroke of the piston 18, and closes upon the reverse stroke thereof. By the alternate opening and closing of the valves 46 and 47 in the respective heads 8 and 9, a 110 continuing pumping action is effected by the rotation of the shaft 15 so long as it is in motion, and constant circulatory fluid flow through the machine, as will presently appear, is thereby maintained.

Said circulatory flow, following the direction indicated by the arrows in the drawings, proceeds downwardly through the alternating operating pipes 26 and 27 from the pipe 25, and upwardly, as is also indicated by arrows, through the alternately active pipes 33 and 34, which make delivery to the pipe 31. The pipe 25, as already specified, communicates directly with the expansion coils 28, with which also the pipe 31 120

communicates, but indirectly through the closed receptacle 6. The pipe 31 discharges directly through the dome 32 into the interior of the receptacle 6, where its fluid contents are converted by condensation from the form of a gas or vapor into that of a liquid. In that state it issues, as from the bottom of the receptacle 6, through a pipe, 66, which is provided with a regulative or 19 cut-off valve 67. A pipe 68, preferably of restricted capacity, leads from the pipe 66 through a suitable expansion valve case 69, of any usual or preferred type, to the coils 28.

20 70 indicates a water inlet pipe and 71 a water outlet pipe which communicate, respectively, with external means of water supply and discharge, not illustrated, and with suitable cooling or condensing coils 72, disposed preferably as shown in Figure 1, within the upper portion of the receptacle 6, within the lower portion of which are maintained, throughout any period of operation of the machine, two still bodies or pools of 25 different circulatory liquids, respectively. The upper pool 74 is composed of a suitable liquid lubricant, for example oil, which a pipe 75 leads into operative communication with the parts of the machine working within the case 2. It floats upon the lower pool 76 which is composed of a refrigerant having a greater specific gravity than the lubricant used, and with which the pipe 68 is in circulatory communication as has been already specified.

30 In the description of the operation of our machine next following is set forth the method which in part constitutes our invention.

40 Assume that the machine has been supplied or replenished as required through the intake port 37, with liquid refrigerant and liquid lubricant in sufficient quantities, respectively, and that the valve of the port 37 has been closed. The valves 29, 38 and 67 being then open, driving power from any suitable motor, not illustrated, is applied to the pulley 16, which, as has been specified, rotates the shaft 15 and the eccentric-head 45 17, with the effect of imparting operative reciprocation to the piston 18. By said reciprocation, in the manner already described in terms sufficiently intelligible to one skilled in the art, movement of the circulating fluid through the circulatory system is set up, and will be maintained so long as operative reciprocation of the piston 18 continues.

50 The refrigerant employed by us, for example, but also by preference, is sulphur dioxid (SO_2). It is heavier than the oil or lubricant used, and constitutes essentially the circulating fluid aforesaid. The valves 46 and 47 divide the circulatory system into the "suction side" and the "compression

side" of our machine, as they are denominated in the common parlance of the art.

With each forward movement of the piston 18, a charge of refrigerant is effectively compressed. In the course of its passage 70 through the circulatory system each charge passes through the expansion valve case 69 when it suddenly expands, in the manner well understood in the art, into a gas or vapor with consequent reduction of temperature in the expansion chamber or coils 28, with refrigerative effect. The said coils are, in practice of course, enclosed in the usual manner which requires only mention.

75 Driven by the combined forces of compression and of suction obtained, as already specified, through the combined operations of the piston 18 and the valves 46 and 47, the charge of refrigerant under contemplation, after undergoing expansion, returns, through the pipe 25 and its respective branches, into the case 2, where, as often as it arrives, it is compressed again and again in each cycle of circulation.

80 The pumping action of the compressor effects substantially constant circulation through movement of successive charges of the circulatory fluid following without interruption one after another.

85 Besides the circulatory movement of the refrigerant, there is constantly supplied a bath of lubricant derived from the pool 74 through the pipe 75 for the working parts of the machine from which a small portion passes by leakage into the circulatory refrigerant. A small quantity of lubricant leakage does not materially affect the reduction of temperature obtained through the expansion of the refrigerant, but it is sufficient, in consequence of its cumulative tendency to form a film-coating on the interior of the coils 28, to impair the efficiency of the machine, even substantially to the point of elimination.

90 To effect substantially perfect separation of the refrigerant and the lubricant is, therefore, made the main object of our invention. The method by which we accomplish that end may be understood from the 95 description next following.

100 In the operation of the machine each successive charge of refrigerant, after having been subjected to the desired degree of compression, passes through the pipe 31 into the receptacle 6, the pressure created by compression being maintained until it passes in liquid form through the pipe 66 and the expansion valve 69 where it becomes rarefied by expansion into a gas or vapor, in which form it is conducted in its circulatory 105 cycle back by the pipe 25 to the compressor.

110 Each compressed charge of refrigerant is liquefied after it enters through the pipe 31 the receptacle 6 in consequence of the presence therein of the cooling coils 72,

whose effect is to condense and precipitate it within the receptacle 6 in the form of a shower. The lower portion of the receptacle being always during the operation of the machine provided with the pools 74 and 76, the minute drops or particles of the circulatory medium, composed mainly of the refrigerant combined with such modicum of lubricant as may be present in it, fall like gentle rain upon the surface of the pool 74. Thereupon the heavier liquid—the refrigerant—is precipitated by gravity towards the bottom of the receptacle where it collects in the pool 76. In the accomplishment of such precipitation the refrigerant is in effect filtered; that is to say, it gives up substantially all the lubricant which it may contain. Finally, after reaching the pool 76, the body of the refrigerant repose in a substantially constant state of static stability, owing to the fact that the pipe 68 is of small capacity, restricted approximately to that of minuteness. Consequently, opportunity is afforded for the buoyancy of the lubricant, if any trace of it perchance remain in the pool 76, to exert itself so as to lift the lubricant out of the refrigerant, and to cause substantially all of it to be incorporated into the body of the lubricant constituting the pool 74.

Moreover, the flow of the refrigerant from the pool 76 is drawn from the very bottom thereof, with the effect, before it enters the pipe 66, of insuring its substantially perfect purification of the lubricant, that is to say, to a degree which will eliminate film-coating of the coils 28.

We find, from repeated and long continued actual tests, that our invention as above specified effects an unimpaired efficiency which in the operation of our machine, may be maintained for indeterminate but substantially unlimited periods of time. Also, that, by reason of the extreme simplicity of the construction of our machine there results in its operation a minimum of wear and therefore practically no occasion for repairs.

It is deemed proper to add that the pools 74 and 76 may be maintained at a depth, respectively, which will insure constantly adequate supplies of refrigerant and of lubricant for the machine to draw upon during operation. Provision may be made, if desired, of familiar means for testing from time to time such variation of the respective levels of said pools as may occur within the receptacle 6, but this if desired is no more than an ordinary mechanical contrivance, which is deemed to be so well-known as to call for neither illustration nor any description other than this passing mention.

What we claim is:

1. As an improvement in the art of refrigeration obtained from successive com-

pression and expansion of a refrigerant, the process which consists in collecting and maintaining in static stability within a refrigerative circulating system, two pools composed, respectively, of two liquids of different specific gravities, namely, a heavier refrigerant and a lighter lubricant, said pools being superposed one above the other so that the lighter lubricant floats on top of the heavier refrigerant, promoting a continuous circulation of the refrigerant through said system, compressing and condensing the refrigerant and, when condensed, showering it in liquid form, together with such of the lubricant as it may contain, upon the lubricant pool whereby it may gravitate therethrough without disturbing the static stability of the pools and may effect substantially perfect separation of the lubricant from the circulatory medium, substantially as set forth.

2. As an improvement in the art of refrigeration obtained from successive compression and expansion of a refrigerant, the process which consists in collecting and maintaining in static stability within a defined refrigerative circulating system two pools composed, respectively, of two liquids of different specific gravities, namely, a heavier refrigerant and a lighter lubricant, said pools being superposed one above the other so that the lighter lubricant floats on top of the heavier refrigerant, promoting a continuous circulation of the refrigerant through said system, compressing and condensing the refrigerant and, when condensed, showering it in liquid form, together with such of the lubricant as it may contain, upon the lubricant pool whereby it may gravitate therethrough without disturbing the static stability of the pool and may effect substantially perfect separation of the lubricant from the circulatory medium substantially as set forth, and removing the refrigerant from its pool for circulation without disturbing the static stability of said pools.

3. As an improvement in the art of refrigeration obtained from successive compression and expansion of a refrigerant, the process which consists in collecting and maintaining in static stability within a defined refrigerative circulating system, two pools composed respectively of two liquids of different specific gravities, namely a heavier refrigerant and a lighter lubricant, said pools being superposed one above the other with the lighter lubricant floating on top of the heavier refrigerant, promoting a continuous circulation of the refrigerant through said system, conducting the lubricant from said pool to the system without disturbing the static stability of the pool, compressing and condensing the refrigerant, substantially excluding from the compressed refrigerant

- the lubricant conducted from the pool to the system, and passing the condensed refrigerant in liquid form, together with such of the lubricant as it may contain, through the lubricant pool without disturbing the static stability of the latter whereby substantially perfect separation of the lubricant from the circulatory medium is effected substantially as set forth. 5
- 10 4. As an improvement in the art of refrigeration obtained from successive compression and expansion of a refrigerant, the process which consists in collecting and maintaining in static stability within a defined refrigerative circulating system two pools composed respectively of two liquids of different specific gravities, namely, a heavier refrigerant and a lighter lubricant, said pools being superposed one above the other with the lighter lubricant floating on top of the heavier refrigerant, promoting continuous circulation of the refrigerant through said system, conducting the lubricant from said pool to the system without disturbing the static stability of the pool, compressing and condensing the refrigerant, substantially excluding from the compressed refrigerant the lubricant conducted from the pool to the system, and when condensed, showering the refrigerant in liquid form, together with such of the lubricant as may have become mixed therewith, upon the lubricant pool without disturbing the static stability of the latter, and permitting the liquid to gravitate through the lubricant to the refrigerant pool, whereby substantially perfect separation of the lubricant from the circulatory medium is effected substantially as set forth. 15
- 20 5. A compressive refrigerating machine comprising a compressor having a piston, a compressing chamber and a lubricant chamber substantially excluded from said compressing chamber, the working parts of said compressor being operatively associated with said lubricant chamber, a condenser chamber, connections between the condenser chamber and said compressor chamber, means for conducting refrigerant from said compressor chamber to said condensing chamber, an outlet for liquid refrigerant leading from the lower part of said condenser chamber, an evaporator in communication with said outlet, and a lubricant connection leading from the intermediate part of said condenser chamber to the lubricant chamber of said compressor, said machine being adapted to circulate the refrigerant from said evaporator through the compressor and then to the condensing chamber substantially out of contact with the lubricant conducted to said lubricant chamber. 25
- 30 6. A compressive refrigerating machine comprising a compressor having a piston, a compressing chamber and a lubricant chamber substantially excluded from said compressing chamber, the working parts of said compressor being operatively associated with said lubricant chamber, a condenser chamber, connections between the condenser chamber and said compressor chamber, means for conducting refrigerant from said compressor chamber to said condensing chamber, an outlet for liquid refrigerant leading from the lower part of said condenser chamber, an evaporator in communication with said outlet, and a lubricant connection leading from the intermediate part of said condenser chamber to the lubricant chamber of said compressor, said machine being adapted to circulate the refrigerant from said evaporator through the compressor and then to the condensing chamber substantially out of contact with the lubricant conducted to said lubricant chamber. 35
- 35 7. A compressive refrigerating machine comprising a compressor having a piston, a compressing chamber and a lubricant chamber substantially excluded from said compressing chamber, the working parts of said compressor being positioned in said lubricant chamber, a condenser chamber connected with said compressing chamber, means for conducting refrigerant from said compressing chamber to the upper part of said condenser chamber, a cooling element in the upper part of said condenser chamber, an outlet for liquid refrigerant leading from the lower part of said condenser chamber, an evaporator in communication with said outlet, and a lubricant connection leading from the intermediate part of said condenser chamber to the lubricant chamber of said compressor, said machine being adapted to circulate the refrigerant from said evaporator through the compressor and then to the condensing chamber substantially out of contact with the lubricant conducted to said lubricant chamber. 40
- 40 8. A refrigerating machine comprising a circulating system operatively including a refrigerant compression member, means for effecting refrigerant expansion, an expansion chamber, and a condensing and separating chamber all operatively included in the circulating system, said condensing and separating chamber having a cooling means and below the same a suitable condensing space, two distinct pools of liquid, one of oil floating upon the other of refrigerant, and each of sufficient volume to permit static stability in each pool, said cooling means being adapted to condense the refrigerant and to permit the same in liquid form to gravitate upon and through said lubricant pool, together with such lubricant as it may contain, a pipe of substantially capillary dimensions for the passage of refrigerant from said pool and its chamber whereby the refrigerant may float from said chamber without disturbing the static stability of its pool, and means of communication between said lubricant pool and said 45
- 50 9. A compressive refrigerating machine comprising a compressor having a piston, a compressing chamber and a lubricant chamber substantially excluded from said compressing chamber, the working parts of said compressor being operatively associated with said lubricant chamber, a condenser chamber, connections between the condenser chamber and said compressor chamber, means for conducting refrigerant from said compressor chamber to said condensing chamber, an outlet for liquid refrigerant leading from the lower part of said condenser chamber, an evaporator in communication with said outlet, and a lubricant connection leading from the intermediate part of said condenser chamber to the lubricant chamber of said compressor, said machine being adapted to circulate the refrigerant from said evaporator through the compressor and then to the condensing chamber substantially out of contact with the lubricant conducted to said lubricant chamber. 55
- 55 10. A compressive refrigerating machine comprising a compressor having a piston, a compressing chamber and a lubricant chamber substantially excluded from said compressing chamber, the working parts of said compressor being operatively associated with said lubricant chamber, a condenser chamber, connections between the condenser chamber and said compressor chamber, means for conducting refrigerant from said compressor chamber to said condensing chamber, an outlet for liquid refrigerant leading from the lower part of said condenser chamber, an evaporator in communication with said outlet, and a lubricant connection leading from the intermediate part of said condenser chamber to the lubricant chamber of said compressor, said machine being adapted to circulate the refrigerant from said evaporator through the compressor and then to the condensing chamber substantially out of contact with the lubricant conducted to said lubricant chamber. 60
- 60 11. A compressive refrigerating machine and condenser having a crank case, a piston, a crank in said case connected with said

compression member adapted to lubricate the working parts of the compression member substantially without bringing the same into direct communication with the refrigerant operated upon by said compression member.

9. A refrigerating machine comprising a circulating system operatively including a refrigerant compression member, an expansion chamber, and a combined condensing and separating chamber all operatively included in the circulating system, said condensing and separating chamber having a capacity to accommodate below a suitable condensing space two distinct pools of liquid, one of oil floating upon the other of refrigerant, and each of sufficient volume to permit static stability in each pool, cooling means within said condensing space to condense the refrigerant and to permit the same in liquid form to gravitate upon and

through said lubricant pool, together with such lubricant as it may contain, a pipe for the passage of refrigerant from said pool and its chamber whereby the refrigerant may pass from said chamber, and means for communication between said lubricant pool and said compression member, said compression member being adapted to receive lubricant for its working parts without bringing the lubricant into direct communication with the refrigerant, and said system being adapted substantially to exclude the refrigerant and lubricant from one another throughout except in said condensing chamber and being adapted to maintain them therein in distinct pools having static stability.

In testimony whereof, we have hereunto set our hands:

JAMES B. THOMPSON.
SELDON B. HIBBARD.
